FLUID CLEANING APPARATUS

Homer E. Thornhill, Houston, Tex., assignor to
 Thornhill-Craver Company, Houston, Tex., a
 corporation of Texas

Application December 3, 1949, Serial No. 131,017

7 Claims. (Cl. 210—167)

1

This invention relates generally to fluid cleaning apparatuses, and particularly to apparatuses for removing foreign matter and solid particles from liquids moving through pipe lines.

Certain cleaning apparatuses now in common use, in oil pipe lines for example, are unsatisfactory in that the screens used therein must be removed in order to be cleaned. The task of removing and cleaning the screens is such that the screens are often left in place after they are in need of cleaning. In certain instances clogged screens have burst by reason of the fluid pressure, and in other instances have been deliberately punctured by workmen wishing to avoid the work of removal and cleaning.

This invention has for one of its general objects the provision of a new and improved apparatus whereby the screens in cleaning apparatuses may be easily, quickly and thoroughly cleaned without removing them from the cleaning apparatus.

A more specific object of the invention is to provide a new and improved cleaning apparatus embodying a screen so constructed and disposed that the foreign matter collecting therein may be swept into a drain, and means to direct a concentrated stream of cleaning fluid under high pressure upon such foreign matter to sweep it into the drain.

Other objects will hereinafter appear.

The preferred embodiments of the invention are illustrated by the accompanying drawings, wherein:

Fig. 1 is a flow diagram illustrating a cleaning apparatus, constructed in accordance with the invention, mounted in a flow line,

Fig. 2 is a longitudinal sectional view of a cleaning apparatus, constructed in accordance with the invention,

Fig. 3 is an end elevation of said apparatus,

Fig. 4 is a transverse sectional view taken on the line 4—4 of Fig. 2,

Fig. 5 is an enlarged detail of the strainer element construction,

Fig. 6 is a schematic diagram illustrating the disposition of the cleaning spray nozzle,

Fig. 7 is an enlarged sectional view of the nozzle,

Fig. 8 is a schematic diagram illustrating the flow path of the cleaning fluid discharged from the spray nozzles,

Fig. 9 is a transverse sectional view of a modified shape of strainer element,

Fig. 10 is a partly sectional elevation of another form of cleaning apparatus embodying the invention,

2

Fig. 11 is a vertical section on the line 11—11 of Fig. 10,

Fig. 12 is a bottom plan view of the nozzle head of the Fig. 11 embodiment,

Fig. 13 is a partly sectional elevation of another form of cleaning apparatus embodying the invention, and

Fig. 14 is a detail view of the nozzle carrier of Fig. 13.

10 Referring to Fig. 1 of the drawing which illustrates the use of the new and improved cleaning apparatus provided by this invention in connection with an oil pipe line, the oil pipe line is indicated by the letter F and a by-pass from said line is indicated by the letters B and P. The pipe B is connected to the inlet pipe 12 of the new and improved cleaning apparatus provided by this invention. The vessel of the cleaning apparatus is illustrated by the numeral 10. The pipe P is connected to the outlet pipe 25 of the cleaning apparatus. It will be apparent that when the valves B₁ and P₁ are closed and the valve 40 is open, the oil will flow directly through the pipe F. If the valves B₁ and P₁ are open and the valve 40 is closed, the oil from the pipe line F will be by-passed through the pipe B, through the cleaning apparatus 10, and back into the pipe F through the pipe P. The numeral 44 indicates a pump to pump cleaning fluid through the pipe

20 45, pipe 36 and into the vessel 10 of the cleaning apparatus. The drain pipe leading from the opposite end of the vessel 10 of the cleaning apparatus is indicated at 22 and it is connected with the settling tank 41. Foreign matter settling in

25 the tank 41 may be withdrawn through the valve 42, and clean fluid from the top of the settling tank 41 may be drawn through the pipe 43 by the pump 44 and pumped through the pipes 45 and 36 back into the vessel 10 of the cleaning apparatus.

30 40 The pipe 36 may be provided with a valve 36a and the pipe 45 with the valve 45a to control the flow of fluid through said pipes. A discharge pipe 46 equipped with a valve 46a may also be provided.

35 Referring now to the embodiment of the cleaning apparatus illustrated by Figs. 2 through 8, wherein like numerals designate like parts, it includes the vessel 10 having an inlet 14 in which the inlet pipe 12 is disposed, an outlet 24 in communication with the outlet pipe 25, a screen 26 disposed between the inlet 14 and the outlet 24, and a drain 21 connected with the drain pipe 22. The end of the screen 26 adjacent the drain 21 is open so that foreign matter accumulating within 45 the screen 26 may be swept out of the screen into the drain 21. Such foreign matter is so swept by

3

the concentrated streams of cleaning fluid issuing under high pressure from the circumferentially spaced nozzles 35 mounted in the partition 15 and in communication with the chamber 16 into which the fluid is pumped through the pipe 36. The chamber 16 is formed by the cover 11 on the end of the vessel 10 which cover 11 may be welded to the inlet pipe 12 as indicated at 13.

The screen 26 is provided with eccentric annular flanges 28 and 30 at the ends thereof so that when the cover 17 at the end of the vessel 10 is opened and the screen 26 is shoved into the vessel 10, the screen will be held a substantial distance from the outlet 24.

The bottom of the vessel 10 may be provided with openings 18 and a false bottom 19 so that such foreign matter as may settle in the vessel 10 below the screen 26 may be withdrawn through the valve 20.

The screen 26 is of a fine mesh and the tubular support 27, perforated as indicated at 32, surrounding the screen 26 forms a backing or support for the screen. The perforations 32 being arranged in annular rows provide in effect annular reinforcing ring elements which have been designated 27a in Fig. 5. A suitable packing member 29 (Fig. 2) may be provided to seal the ring 28 to the end of the tubular support 27, and a similar ring 31 may be provided between the annular ring 30 and the opposite end of the tubular support 27. Or if desired, the eccentric annular rings 28 and 30 at the ends of the tubular member 27 may be integral with said member.

Referring now to the structure and function of the nozzles 35 which as above indicated function to discharge cleaning fluid upon the interior surface of the screen 26 to sweep therefrom into the drain 21, the fine particles of foreign matter which collect upon the interior surface of the screen when the oil containing the same passes through the screen. In Fig. 7 the body of the nozzle is indicated at 35 and its axial bore at 35b. These nozzles are so mounted in the partition 15 that they are at an angle to the longitudinal axis of the screen and are also inclined in a direction toward the interior surface of the screen 26. The inclination of the nozzles 35 will be apparent from Fig. 6 in which the plane occupied by the partition 15 is indicated at 15p. The inclination will also be apparent from Fig. 8 which illustrates the spiral path S of the fluid issuing from the nozzles 35 upon the interior surface of the screen 26. Thus the stream of cleaning fluid ejected by each nozzle is not only directed into contact with the inner surface of the screen 26 but is also directed in a generally spiral path S along the interior thereof. This results in a thorough cleansing action which will remove all of the particles which may have adhered to the screen during the straining operation, the said particles being thereby swept by the cleaning fluid into the drain 21.

When it is desired to clean the screen, the valve 40 (Fig. 1) is preferably opened and the valves B1 and P1 closed. That part of the flowing fluid then in the vessel 10 may be drained therefrom through the valve 20 (Fig. 2) and an air valve 50 may be provided in the top of chamber 10 so that the flowing fluid will readily flow through the valve 20 when the valves 20 and 50 are open. After the flowing fluid has been thus drained from the vessel 10, the valves 20 and 50 may be closed and the pump 44 (Fig. 1) operated to pump cleaning fluid into the screen 26 to sweep the

4

foreign matter therefrom into the drain 21. However, while it is considered preferable to drain the flowing fluid from the vessel 10 as just stated, the cleaning fluid may be pumped into the screen while the flowing fluid is in the screen.

Referring now to Fig. 9 which illustrates another embodiment, the numeral 51 indicates a screen and the numeral 52 a tubular support, which are hexagonal in cross section. It will be obvious that the tubular screen and its support may be made of any desired cross sectional shape.

Referring to Figs. 10, 11 and 12 wherein like numerals designate like parts, and which illustrate another embodiment of the invention, the vessel is indicated at 100, the inlet at 102, the outlet at 103, the screen at 104 and the drain at 105.

At the top of the vessel 100 is a removable cover 106 which has a partition 107 forming cleaning fluid chamber 108. Cleaning fluid may be pumped into the chamber 108 through the pipe 109 and it will be discharged through the nozzles 110 upon the inner surface of the screen 104 to sweep the foreign matter therefrom into the drain 105.

In order to permit the flowing fluid to be drained from the vessel 100 before the cleaning fluid is discharged into the screen, an air bleed pipe 111 may be provided in the removable cover 106. It will be understood that the cleaning fluid pipe 109 may be connected to a pipe such as the pipe 36 shown in Fig. 1, and that the air bleed pipe 111 may be provided with a valve such as that indicated at 50 in Fig. 2.

The screen 104 may be inserted in the vessel 100 when the cover 106 is removed, and the lower ring 112 on the screen will fit within the supporting ring 113. The chamber 114 in the bottom of the vessel is separated from the space surrounding the screen 104 by the partition 115. The top of the screen 100 may be provided with a ring 116 to be engaged by the partition 107 whereby the screen is held in place.

It will also be understood that in the Fig. 10 through 11 embodiment the inlet pipe 102 may be connected to a by-pass pipe such as the pipe B shown in Fig. 1; the outlet pipe 103 to a by-pass pipe P such as shown in Fig. 1 and the drain 105 to a pipe such as pipe 22 shown in Fig. 1.

Referring to the embodiment illustrated by Figs. 13 and 14 in which like numerals designate like parts, the vessel is indicated at 200, the inlet at 202, the outlet at 203, the screen at 204 and the drain at 205. The numeral 206 indicates an air bleed connection such as the connection 50 in Fig. 2. In this embodiment a single nozzle 210 is carried by a carrier 211 which is mounted on a pipe 212 extending outwardly through a stuffing box 213 in the removable cover 214. The pipe 212 is rotatable and reciprocable in the stuffing box 213 and is provided with a handle 215 accessible from the exterior of the vessel 200. It will be apparent that the nozzle carrier 211 may be rotated by means of the handle 215 to move the nozzle 210 in a circular path adjacent the interior surface of the screen 204 and that the cleaning fluid issuing from the nozzle 210 may be thereby played upon different areas of the interior surface of the screen. It will also be apparent that the nozzle carrier 211 may be moved back and forth in the screen 204 to carry the nozzle 210 longitudinally closer to different areas of the internal surface of the screen to be swept by the cleaning fluid.

It will be apparent that in the embodiment shown by Figs. 13 and 14, the inlet 202 may be connected to a by-pass pipe such as the pipe B shown in Fig. 1; the outlet 203 to a by-pass pipe such as the pipe P shown in Fig. 1; the drain 205 to a drain pipe such as the pipe 22 shown in Fig. 1, and that the pipe 212 may be connected by the flexible hose 216 to a cleaning fluid pipe such as the pipe 36 shown by Fig. 1.

It will be apparent from the foregoing that this invention provides a new and improved cleaning apparatus, the screen of which may be thoroughly, quickly and easily cleaned without removing it from the cleaning apparatus.

The invention is not limited to the preferred embodiments herein disclosed. Various changes within the scope of the following claims will occur to those skilled in the art.

I claim:

1. A cleaning apparatus including an elongate vessel closed at its ends and having an inlet, an outlet, and a drain disposed laterally of said vessel, a tubular screen eccentrically disposed with respect to said vessel between said inlet and outlet and having one end thereof opening toward said drain, a transverse partition in said vessel adjacent said inlet forming a chamber between said partition and that end of the vessel adjacent said inlet, a plurality of nozzles disposed in said partition concentrically with respect to said inlet and further disposed at an acute angle with respect to the interior surface of said screen and at an angle relative to the longitudinal axis of said screen, and cleaning fluid means separate from said inlet and in communication with said chamber and nozzles to discharge a concentrated stream of cleaning fluid through and upon the interior surface of said screen and out of the end of said screen which opens toward said drain to sweep foreign matter from said screen into said drain.

2. A cleaning apparatus including an elongate vessel closed at its ends and having an inlet, an outlet, and a drain disposed laterally of said vessel, a tubular screen eccentrically disposed with respect to said vessel between said inlet and outlet and having one end thereof opening toward said drain, an air vent in said vessel normally closed but when opened adapted to permit drainage of flowing fluid from said vessel, a transverse partition in said vessel adjacent said inlet forming a chamber between said partition and that end of the vessel adjacent said inlet, a plurality of nozzles disposed in said partition concentrically with respect to said inlet and further disposed at an acute angle with respect to the interior surface of said screen and at an angle relative to the longitudinal axis of said screen, and cleaning fluid means separate from said inlet and in communication with said chamber and nozzles to discharge a concentrated stream of cleaning fluid, after the flowing fluid has been drained from said vessel, through and

upon the interior surface of said screen and out of the end of said screen which opens toward said drain to sweep foreign matter from said screen into said drain.

3. A cleaning apparatus as set forth in claim 2, in which each stream directed by each nozzle is directed into contact with the interior surface of the screen at an acute angle relative thereto.

4. A cleaning apparatus as set forth in claim 2, in which each stream directed by each nozzle is directed into contact with the interior surface of the screen at an acute angle relative thereto and is caused to traverse a spiral path about said interior surface of said screen.

5. A cleaning apparatus including an elongate vessel having an inlet, an outlet, and a drain, a tubular screen disposed with respect to said vessel between said inlet and outlet and having one end thereof opening toward said drain, and cleaning fluid means separate from said inlet and in communication with a nozzle and a nozzle carrier, said carrier being rotatable to cause said nozzle to discharge a concentrated stream of cleaning fluid through and upon different areas of the interior surface of said screen and out of the end of said screen which opens toward said drain to sweep foreign matter from said screen into said drain.

6. A cleaning apparatus as set forth in claim 5 in which said nozzle carrier is reciprocable longitudinally along the axis of said screen.

7. A cleaning apparatus including a vertically disposed elongate vessel having an inlet, an outlet, and a drain, a tubular screen eccentrically disposed with respect to said vessel between said inlet and outlet, the lower end of said screen opening toward said drain, an air vent in said vessel normally closed but when opened adapted to permit drainage of flowing fluid from said vessel, and cleaning fluid means separate from said inlet and in communication with a plurality of nozzles adjacent one end of said screen to discharge a concentrated stream of cleaning fluid downwardly through and upon the interior surface of said screen and out of the end of said screen which opens toward said drain to sweep foreign matter from said screen into said drain.

HOMER E. THORNHILL.
